UNITED STATES PATENT OFFICE.

CHARLES SCOTT ALTHOUSE, OF READING, PENNSYLVANIA.

HOSIERY FIGURE DYEING AND EXTRACTING MACHINE.

No. 885,709.

Specification of Letters Patent. Patented April 28, 1908.

Application filed December 4, 1905. Serial No. 290,107.

To all whom it may concern:

Be it known that I, CHARLES SCOTT ALTHOUSE, a citizen of the United States, residing in the city of Reading, county of Berks, 5 and State of Pennsylvania, have invented certain new and useful Improvements in Hosiery Figure Dyeing and Extracting Machines, of which the following is a specification.

10 My invention relates particularly to improved mechanism for effecting the figure-dyeing-and-extracting of ornamented stockings; my main objects being to secure more accurate, satisfactory, and rapid work, while 15 dispensing entirely with expert hand labor.

The invention is fully described in connection with the accompanying drawings, and the novel features are specifically pointed out in the claims.

20 Figure 1 is a side elevation, partly in section, of the main portions of a machine embodying my invention. Fig. 2 is a corresponding front elevation, looking in the direction of the arrow, Fig. 1.

25 Between the side frames 2 2 which are rigidly connected by the spaced cross-pieces 3, 4 and 5, extend a pulley shaft 6, a main shaft 7 rotated thereby, and similar cam-shafts 8 8 and a crank-shaft 9 all suitably driven from 30 said shaft 7; such shafts being employed in the specific construction shown, to operate the essential elements of the machine as hereafter described.

35 The stockings to be operated upon in figure-dyeing and extracting, are commonly stretched upon board formers, and dye-blocks carrying the desired designs, after having the required dye (or dye-extracting material as the case may be) applied thereto, 40 are carefully placed in proper position upon them and the impression, or successive impressions in different colors, made. My invention provides for making any desired number of impressions in passing the stockings through a single machine, the successive 45 operations being effected automatically and with absolute accuracy without requiring special skill or care on the part of the operator.

50 The boarded stocking 10 is firmly placed in required position upon a fabric-carrier plate 11 which is moved horizontally, as hereafter described, in suitable guide-ways 12 provided on the frame 2 2. A dye-block or 55 blocks, 13 and 13 as shown in the drawing,

are adjustably fixed to separate carrier-bars 14 the ends of which are guided in vertically-slotted housings 15 fixed to the machine frame above the horizontal guide-ways, 12, so as to permit of vertical movements of each 60 dye-block as desired; such movements being effected in harmony with the fabric-carrier movements and with the action of the dye-feed belts, as hereafter described. These latter, which serve to apply the desired dye or extracting material to each dye-block prior to the making of each impression, consist as shown of separate strips 16 of absorbent fabric, arranged in the form of endless belts and each carried upon a pair of 65 drive-rolls 17 17 therefor, located below the fabric-carrier guide-ways 12. Each of these pairs of drive-rolls is rotatably mounted in suitable bearings 18 18 provided on a wall-bracket 19, which projects laterally from a 70 side-frame 2 of the machine a sufficient distance to permit of employing a proper width of belt to contact with the whole surface of the dye-block employed; said bracket and its drive rolls however being shorter than the 75 space between the spread side-frames 2 2 so as to permit of readily placing and removing the endless feed-belts 16 upon the drive-rolls as shown. The slack portion of each feed-belt, when applied to the drive-rolls, 80 dips into a dye-reservoir 20, suitably secured beneath the same, and is kept more or less taut as desired by means of a suitable tension roll 21, which is located within the dye-reservoir upon the slack of the moving belt; 85 said tension roll serving to stretch the belt fabric as required to insure proper feed of the dye or extractor material to the dye-block when the latter is brought into contact with it for that purpose. Any suitable yielding 90 backing 22 may be provided beneath the flat portion of the belt to equalize the supply of dye to the contacting surface of the dye-block.

An intermittent reciprocating movement 100 is imparted to the fabric-carrier plate 11, as shown, by means of a pair of levers 25, pivoted at their lower ends 26 to the frame, and having their slotted upper ends 27 connected to projecting trunnions 28 on the 105 carrier; the required movements being transmitted to said levers from the crank-shaft 9, the crank-pin 31 of which engages the intermediate slotted portion 29 of the lever. To provide for (1) moving the fabric-carrier into 110

proper position beneath the nearer dye-block, (2) for retaining it in such position while the first impression is being made upon the fabric, (3) for a further similar movement 5 to the next dye-block, and finally for a quick return of the fabric-carrier to its original position, I employ in the construction shown, suitably mutilated gears arranged upon the operating shafts 7 and 9 as required; the 10 crank-pin 31 being rotated in the direction indicated by the arrow, first to the position 31^a, second to the position 31^b, and finally returned in a single movement to the normal position shown.

15 The duplex movement required to be imparted to each dye-block in proper time with the successive movements of the fabric-carrier, is transmitted through separate connecting-rods 35 attached at their upper ends 20 to projecting pins 36 on the dye-block carrier bars 14. As shown the lower ends of these rods are connected at 37 37 to similar levers 38 separately pivoted at 39 39 to the frame, and provided intermediate of their length 25 with friction rollers 40, upon each of which a double cam 41—42 upon a cam-shaft 8, is arranged to operate; the cam 41 serving to depress said lever 38 and its connected dye-block sufficiently to bring the latter into 30 contact with its feed-belt 16, and the cam 42 to thereafter depress it into contact with the interposed fabric upon the carrier. The springs 43 serve to raise the respective dye-blocks when the cams are out of service, and 35 sleeve-nuts 44 upon the connecting rods 35 permit accurate adjustment of their lengths as required. In the construction shown the actions of the cams 41—42 are properly timed to the different positions assumed by 40 the fabric-carrier 11, by means of suitable mutilated gears such as previously referred to as operating the crank-shaft 9.

To provide for moving the feed-belts and for stopping their movement at the moment 45 of contact of either dye-block therewith, I employ a countershaft 50 having a worm-gear connection to each drive-roll and operated from the main shaft 7 through a suitably mounted vertical drive-rod 51; said rod being 50 formed in two parts normally connected by a clutch 52 so as to be rotated with said main shaft, but adapted to be disconnected by the operation of a clutch-lever 53. The lower end 54 of this clutch-lever is arranged in the 55 path of similar fingers 55 provided on the cam-levers 38, so as to be depressed during the final downward swing of said levers sufficiently to free the clutch 52 just as the dye-block comes into contact with the feed-belt, 60 thus stopping the latter until the dye-block begins to rise when the clutch is again thrown into engagement by a spring 56 and the movement of the feed belt is promptly resumed.

The co-operative action of the several parts 65 of the machine may be further described as

follows: The boarded fabric 10 is properly placed upon the carrier 11, to which a step-by-step forward movement and continuous return movement are imparted by the engaging crank-pin 31 of shaft 9; these movements being effected by omitting series of teeth on the constantly rotating main shaft gear wheel which drives said shaft 9, in a manner commonly employed and well understood by mechanics, and which is therefore not specifically set forth. Before the first forward movement of the carrier occurs, the first dye-block has been lowered by the cam 41, into contact with its dye-feed belt 16, and then raised; the fabric 10 being thereafter moved into position directly below the inked block by the swing of the crank pin 31 to position 31^a, and being detained there (during the ineffective rotation of the mutilated drive gear) until the inked block has been lowered a second time by the action of cam 42, into printing contact with the interposed fabric. As the block is raised again (after the passing of cam 42), the second forward step of the fabric carrier occurs, to bring the fabric 10 in like manner below the second similarly inked block, where it is again detained for the second impressing or printing-action. As shown in the drawing these two forward steps only are provided for, and the further swing of the crank pin 31, from position 31^b, causes a single quick return movement of the carrier to the normal position indicated in Fig. 2; the series of dye-blocks being retained in raised position until this movement is effected, and 95 their alternate inking and impressing movements being then successively repeated in proper times with the carrier movements as just described, and also with the respective intermittent dye-feed belt movements as previously explained. Both the inking and the impressing movements of the several dye-blocks are effected successively, and are separately timed to move into contact with the dye-feed belts when the fabric carrier is out 100 of the way, and with the interposed fabric when the carrier is momentarily at rest below it; the separate main-shaft drive gears for the cam shafts 8 and 9, being independently adapted to properly time the dye-block movements in similar manner to the crank-shaft 9 and as will be readily understood by mechanics.

The mechanism particularly shown and described may evidently be readily modified 110 without departing from my invention as specifically defined in the subjoined claims.

What I claim is:—

1. The combination of a plurality of dye-blocks and dye-applying means therefor, a 115 fabric carrier mechanism for successively moving said carrier into position between each of said dye-blocks and its dye-applying means, and mechanism for successively moving each of said dye-blocks first into contact 120

with its dye-applying means and thereafter into contact with the interposed fabric upon the carrier.

2. The combination of a plurality of vertically movable dye-blocks, a horizontally movable fabric carrier, dye-applying means located below said blocks and the plane of the carrier, mechanism for imparting to each block alternate dye-taking and impressing movements, and mechanism for imparting a step-by-step forward movement and a continuous return movement to the carrier, and mechanism for imparting an intermittent movement to each belt timed to the respective dye-taking movements; said carrier movements being timed to clear the respective dye-taking block movements, and to coöperate with the respective dye-impressing block movements, substantially as set forth.

3. The combination of a plurality of vertically movable dye-blocks, a horizontally movable fabric carrier, dye-feed belts located below the respective blocks and the plane of the carrier, mechanism for imparting to each block alternate dye-taking and impressing movements, mechanism for imparting a step-by-step forward movement and a continuous

return movement to the carrier, and mechanism for imparting an intermittent movement to each belt timed to the respective dye-taking movements; said carrier movements being timed to clear the respective dye-taking block movements, and to coöperate with the respective dye-impressing block movements, substantially as set forth.

4. The combination with the supporting side frames and the fabric carrier and dye-block extending between the same, of a drive-roll bracket projecting laterally from one of said frames below said dye-block, drive rolls mounted in said bracket; an endless dye-feed belt carried upon said rolls and laterally removable therefrom past the free end of the bracket, and a dye-reservoir into which said belt dips, substantially as set forth.

In testimony whereof, I affix my signature, in the presence of two witnesses.

CHARLES SCOTT ALTHOUSE.
